UNITED STATES PATENT OFFICE.

MAX FUSS, OF BERLIN, GERMANY.

OZONIZING APPARATUS.

1,017,258.

Specification of Letters Patent. Patented Feb. 13, 1912.

Application filed February 16, 1911. Serial No. 608,925.

To all whom it may concern:

Be it known that I, MAX FUSS, engineer, a subject of the German Emperor, residing at 30 Steinmetzstrasse, Berlin, Germany, have 5 invented new and useful Improvements in Ozonizing Apparatus, of which the following is a specification.

My invention relates to an ozonizing apparatus which differs from all other apparatus 10 hitherto known by its great simplicity and its safe working.

Ozone is produced from the oxygen in the atmosphere by electric action through the action of violet rays. For thus producing 15 ozone a high-tension transformer and a condenser are required. Between the plates of the condenser the silent discharges are formed, which have the property of converting oxygen into ozone. The molecule of oxygen 20 consists of 2 atoms $O = O_2$; one molecule of ozone consists of 3 atoms $O = O_3$. 3 molecules of oxygen will under the action of the silent discharges form 2 molecules of ozone.

25 In the ozonizing apparatus hitherto known a high-tension transformer and an ozonizer connected to the high-tension wire of the transformer are employed. These apparatus are employed either separate and connected by high-tension conductors or they are combined in a common casing. The casing is necessary, because it would be fatal, if the operator were to touch the high-tension wires or the ozonizer.

35 The ozonizer according to my invention dispenses with the casing and there is no danger whatever in touching the apparatus. This is the result of the fact, that the ozonizer, that is the condenser, surrounds the 40 high-tension coil of the transformer. The condenser acting as ozonizer is composed of a tube of glass or other di-electric material lined on the inside with metal foil and an outer slotted metallic tube. Between the 45 glass tube and the metallic tube a small air gap is left in which the violet rays are formed and the oxygen is ozonized. The high-tension wire of the transformer is connected to the metallic lining on the inside 50 of the glass tube, while the leading in wire of the high-tension coil is connected to the iron core of the transformer and the outer metallic tube of the ozonizer. In consequence of such connection the outer tube

of the ozonizer surrounding the high-tension 55 coil will receive the potential of its base, that is the earth potential. The apparatus may therefore be touched without danger.

Referring to the drawings in which like reference letters designate like parts 60 throughout the several views, Figures 1 and 2 are a side view and a top view respectively of such an ozonizing apparatus with arrangement for sucking off the ozone produced. Figs. 3 and 4 illustrate an ozonizing apparatus according to my invention with a perforated outer condenser shell. Figs. 5 and 6 illustrate an ozonizing apparatus according to my invention with a fan 65 fitted thereto.

70 According to Figs. 1 and 2, 1 is the iron core of the transformer with the low-tension winding 2 and the high-tension coil 3; the latter is surrounded by the glass tube 4 of the condenser to the inside metallic lining 75 of which the end of the high-tension coil is connected, while the commencement of the same is connected to the metallic cylindrical tube 5 and the iron core 1. The ozone generated by the high-tension current in the 80 gap between glass tube 4 and metallic tube 5 by means of the silent discharges is sucked off through tube 6. The apparatus is secured to a base-plate 7.

85 If the outer shell of the condenser of the ozonizer is perforated as shown in Figs. 3 and 4 and Figs. 5 and 6, the air flowing past will be ozonized and for small localities, like bed- or living-rooms, it will be quite sufficient to employ such an apparatus without a 90 fan. If a fan 10 is placed in front of the ozonizer, it will be possible, to ozonize the air in large localities in a comparatively short time.

95 For ozonizing distant localities the ozonizing apparatus shown in Figs. 1 and 2 of a suitable size may be combined with a centrifugal fan, which sucks the ozonized air from the ozonizer say through tube 6 and sends it under a certain pressure through 100 conduit tubes to the localities to be ozonized. Such an apparatus will also be adapted to produce highly ozonized air for the sterilization of water, whereas the apparatus according to Figs. 3 and 4 and Figs. 5 and 6 105 are suitable for ozonizing air only. Figs. 5 and 6 specially show a fan 10 fitted directly on the new ozonizing apparatus by means

of standards 9 on a base 7 common to both, so that the apparatus forms an ozonizing fan for ozonizing the air.

I claim:

- 5 1. In an ozonizing apparatus, a transformer having a high tension coil, and a condenser acting as ozonizer, the said condenser being arranged so as to surround the high tension coil of the transformer.
- 10 2. In an ozonizing apparatus, a transformer having a high tension coil, and a condenser acting as ozonizer, said condenser consisting of a tube of dielectric material lined on the inside with metal foil and arranged to surround the high tension coil of the transformer and a metallic tube surrounding said tube of dielectric material, an air gap being formed between said tubes.
- 15 3. In an ozonizing apparatus, a transformer provided with a high tension coil, and a condenser acting as ozonizer, said condenser consisting of a tube of dielectric material having a metal lining on its inside and arranged to surround the high
- 20 25 tension coil of the transformer and a metal tube surrounding said tube of dielectric material and spaced apart therefrom so as to form an air gap therebetween, the high ten-

sion wire of the transformer being connected to said metal lining, and the leading-in wire of the high tension coil being connected to the iron core of the transformer and said outer metallic tube.

4. In an ozonizing apparatus, a transformer provided with a high tension coil, and a condenser acting as ozonizer, said condenser consisting of a tube of dielectric material having a metal lining on its inside and arranged to surround the high tension coil of the transformer and a metal tube surrounding said tube of dielectric material and spaced apart therefrom so as to form an air gap therebetween, the high tension wire of the transformer being connected to said metal lining, and the leading-in wire of the high tension coil being connected to the iron core of the transformer, and said outer metallic tube being slotted so as to afford the passage of air.

In testimony whereof I have signed my name to this specification in the presence of two subscribing witnesses.

MAX FUSS.
